FOREIGN PATENT DOCUMENTS

WO 01084779 A2 11/2001

Primary Examiner — George J Ulsh*Assistant Examiner* — Andrea Marie McKay(74) *Attorney, Agent, or Firm* — Bryan L. Baysinger; Eric Mills; Maynard Nexsen PC(57) **CLAIM**

The ornamental design for a point of sale device, as shown and described.

DESCRIPTION

FIG. 1 is a front perspective view of a point of sale device, showing my new design;

FIG. 2 is a back perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof; and,

FIG. 8 is a right side view thereof.

The broken lines depict portions and environmental subject matter of the point of sale device that forms no part of the claimed design.

1 Claim, 7 Drawing Sheets(56)
